UNITED STATES PATENT OFFICE.

ALBERT F. DAUM, OF PITTSBURGH, PENNSYLVANIA.

FUSE-PLUG.

1,351,204.

Specification of Letters Patent. Patented Aug. 31, 1920.

Application filed September 12, 1914. Serial No. 861,414.

To all whom it may concern:

Be it known that I, ALBERT F. DAUM, a citizen of the United States, residing at Pittsburgh, in the county of Allegheny and 5 State of Pennsylvania, have invented certain new and useful Improvements in Fuse-Plugs, of which the following is a specification.

My invention relates to improvements in 10 fuse plugs, and has particular relation to devices of this type which are refillable at the will of the user.

Among the objects of my invention are to 15 provide a fuse plug which can be readily refilled; which requires no tools in securing the fuse in position or removing a blown fuse; which will provide for efficient contact; in which the fusible element will be retained attached to the plug when removed; 20 in which a fuse strip may be employed; and which can be manufactured and maintained in service at a minimum cost.

To these and other ends, the nature of 25 which will be readily understood as the invention is hereinafter disclosed, my invention consists in the improved construction and combination of parts hereinafter fully described, illustrated in the accompanying drawings, and more particularly pointed out 30 in the appended claims.

In the drawings, in which similar reference characters indicate similar parts in each of the views,—

Figure 1 is a vertical sectional view of a 35 fuse plug according to one form of my invention.

Fig. 2 is a top plan view of the same with the cap removed.

Fig. 3 is a detail view of a fuse strip 40 which may be employed.

Fig. 4 is a view taken at right angles to Fig. 1, showing a slight modification.

Fig. 5 is a top plan view of the same with the cap removed.

Fig. 6 is a detail sectional view showing a modified form of positioning the outer end 45 of the fuse on the shell.

Fig. 7 is a detail sectional view showing the fuse in the form of a wire.

Owing to the necessity of replacing the 50 plugs as an entirety when the fuse element blows, the cost of maintaining service through the use of plugs has been an expensive matter, especially where the installation is such as to provide for carrying heavy loads. To overcome these objections

attempts have been made to apply the refillable idea to this type of protective devices, thus reducing maintainance expense to the cost of the fusible elements, the casing 60 and cap being retained for further service. These devices, however, so far as I am aware, have generally had features which in one way or another acted to prevent commercial adoption generally. Among these 65 features are the fact that the arrangements are such as to require the use of tools in positioning or removing the fusible element, with liability of short-circuiting the leads by the tool, the liability of receiving a shock, 70 and the necessity for care in manipulating the parts; the use of a number of movable parts which are liable to become lost, or which, when being manipulated, are liable to become damaged; and, finally, the excessive cost of manufacture, due to the requirement for drilling holes, threading them, 75 the use of threaded members to enter the holes, the accurate positioning of parts, etc., all of which combine to increase the initial 80 cost as well as necessitate the expenditure of considerable time in removing the blown fuse and refilling the plugs. These disadvantages are overcome in the present invention by the following construction and arrangement of parts.

In the drawings, 10 designates a plug casing of suitable insulating material, such as porcelain, said casing being hollow as shown, and provided with the usual threaded ferrule 11 forming one of the terminals of the fuse plug, coöperating with the socket as is usual with this type of structures. The casing is provided with an external longitudinal slot or recess 12 in which is located the angular conductor 13^a having one end secured to the ferrule 11, the opposite end, indicated at 12^a, extending laterally through the casing at or adjacent the open end of the casing into the casing interior, said end 12^a 100 being preferably provided with a recess 12^b, positioned at the free end or at the side, as may be desired, this recess being adapted to receive the fuse, indicated at 13, either in the form of a strip or of wire, as desired. 105

The closed end of the casing is provided with a teat or projection 14, preferably integral with the casing, and extending through the closed end, adjacent the teat, is a slot or opening 15 through which the fuse is 110 adapted to extend. If desired, the closed end may have an additional depression of

suitable type, indicated at 16 in Fig. 6, into which the outer end of the fuse may extend, said depression being of any desired form, that shown in Fig. 6 being simply an example.

The open end of the casing is closed by the usual cap 17, preferably provided with an opening 17^a, and the usual disk 18 of mica or other insulating material.

As shown, the arm or end 12^a is so located relatively to the disk 18, as to cause the latter, as the cap is threaded to position, to approach the arm or end sufficiently close as to clamp the fuse 13 between the disk and arm, the support afforded the disk by the annular portion of the cap being sufficient to prevent the disk being damaged during the clamping action. As the disk is of a size to project outwardly beyond the fuse, it will be understood that the latter is not liable to pass into contact with the metallic portion of the cap. And since the arm 12^a is of extended area and of proper cross-section to provide a good conductor, the extended contact of fuse and arm will provide sufficient metallic contact to prevent blowing adjacent the cap.

A preferred form of fusible element is shown in Fig. 3 in the form of a strip 13. This may be of the usual form, having parallel sides throughout its length, but I prefer to form the strip with a lateral enlargement adapted to form a shoulder 13^a, said shoulder forming an abutment to prevent a free passage of the fuse through the slot or opening 15, this feature being of advantage in preventing the exposed end of the fuse dropping out during removal of the plug after the fuse has blown, the shoulder being located on the inner side of the closed end and consequently retaining the free end of the blown fuse in position while the plug is being withdrawn, thus preventing any necessity of "fishing" for the free end, or of short-circuiting the leads by the free end or the tool used in the "fishing" operation. An alternative means for providing this result with the strip of usual form is to place a "kink" in the strip to prevent its passage through the slot. Where the fuse is in the form of a wire strand or strands, as in Fig. 7, this "kinking" structure is preferred.

By scoring the strip, as at 13^b, a spool of fusible material may be used to supply fusible elements of various capacity, it being necessary to split the element along one of the lines to decrease the capacity to the desired extent.

As shown in the drawings, the fuse has one end passed through the slot 15 and brought across the face of the seat or projection 14, this forming the opposite terminal of the plug, the other end of the fuse being carried over the outer face of the arm or end 12^a,

being seated in the recess 12^b, and clamped to position by the threading of the cap to position.

By this arrangement it will be readily understood that the cost of manufacture is small, the ferrule and cap being of usual construction, while the conductor is of a form readily stamped out; the plug is of a form which can be readily molded; the assembling of parts is simple requiring only a securing of the conductor to the ferrule. Of these parts the only removable portions are the cap and mica disk and these are of a size and shape not readily lost and are so manipulated as to be practically free from damage.

As will be readily understood, the positioning of the fuse or its removal requires no tools or implements, it being necessary only to remove the cap and disk, place the fuse in position and restore the cap. Upon blowing of the fuse, the plug is removed in the usual manner, carrying the free end with it, the fuse removed and replaced by another and the plug restored to position.

While I have shown several ways in which my invention may be carried out, it will be understood that changes and modifications therein may be required or desired to meet the exigencies of use, and I desire to be understood as reserving the right to make any and all such changes and modifications as may be so required, in so far as the same may fall within the spirit and scope of the invention as expressed in the accompanying claims.

Having thus described my invention, what I claim as new is:

1. In a fuse plug having a cap, a terminal conductor carried by the plug and extending within the plug body with its inner end approaching the axis of the plug, said terminal coöperating with the cap in clamping the fusible element in position.

2. In a fuse plug, a hollow casing having a fixed terminal leading to the interior of the casing, and a removable cap for the open end of the casing, said terminal having its inner end approaching the axis of the plug within the interior of the casing to coöperate with the cap in clamping the fusible element in position.

3. A refillable fuse plug comprising a hollow casing having a closed end perforated for the passage of the fusible element and having an external non-metallic seat for the element, the element passageway being out of alignment with said seat, a fixed terminal carried by the casing and projecting into the casing at its open end, and a removable cap and insulating disk for such open end, said cap and disk coöperating with the terminal to clamp the fusible element in position.

4. In a fuse plug, a hollow casing having a fixed terminal projecting into the casing

at its open end, and a removable cap and disk for closing said end, said terminal having a recess to receive the fusible element and prevent its shifting, and being positioned to coöperate with the cap and disk in clamping the fusible element in position.

5. In a plug fuse and in combination, a hollow casing having a fixed terminal, said casing having a closed end provided with an 10 external seat and being perforated adjacent the seat, a removable cap and disk to close the open end of the casing, and a fusible element having an off-set intermediate its ends, said element having one end clamped by 15 said terminal and the cap and disk, and having its opposite end leading through the perforation of the casing end and seated on said seat, said off-set forming an abutment internal of the casing to retain the free end 20 of the element upon blowing of the element.

6. A fusible element for fuse plugs having an off-set intermediate its ends and extending in the facial plane of the element, said off-set being positioned to form a supporting abutment for the element within the 25 element-disrupting chamber of the plug.

7. In a fuse plug, a hollow casing having a permanently closed end provided with an external seat for a conducting element, said closed end being perforated for the passage 30 of the element and having a recess adapted to receive the free end of the element, said passage and said recess being spaced apart by said seat.

8. A renewable fuse plug including a 35 chambered body-member having an aperture in its wall, in combination with a separable fuse-strip having an intermediate portion disposed within the chamber of the body-member and an end-portion disposed in said 40 aperture, and means on the strip for normally holding the strip from endwise movement through said opening, said means being also disposed within the chamber of the body-member and engaging with the inner 45 face of the wall thereof.

In testimony whereof, I affix my signature in the presence of two witnesses.

ALBERT F. DAUM.
